(57) **CLAIM**

The ornamental design for a cuff bracelet, as shown and described.

DESCRIPTION

FIG. 1 is a top view of a cuff bracelet;

FIG. 2 is a bottom view of the cuff bracelet;

FIG. 3 is a top perspective view of the cuff bracelet;

FIG. 4 is a front view of the cuff bracelet;

FIG. 5 is a side view of the cuff bracelet; and,

FIG. 6 is another side view of the cuff bracelet.

The broken lines shown in the drawings illustrate portions of the cuff bracelet that form no part of the claimed design.
